ATTORNEY.

UNITED STATES PATENT OFFICE

ANNA KNEZ, OF DETROIT, MICHIGAN

KEY FASTENER

Application filed February 4, 1929. Serial No. 337,228.

This invention relates to improvements in key fasteners, and aims to provide a device which can be cheaply and easily manufactured to prevent a key from being turned in its lock into such position that it can be removed therefrom. The invention consists essentially in one piece of flexible wire having a loop intermediately of its length adapted to rest on the shank of a door knob, and downwardly extending legs or ends to pass through the usual opening provided in the outer end of a key to prevent the latter being turned into a vertical position.

The invention is hereinafter more fully described with the aid of the accompanying drawings, in which:

Figure 1 shows a front view of the invention in position, and

Figure 2 is a side view thereof.

Referring to the drawings, 1 designates a portion of a door having a door plate 2 thereon from which a conventional door knob 3 projects; 4 indicates the shank portion of the knob. In the keyhole 5 a conventional key 6 is arranged through the outer end of which a usual opening 7 is formed.

The invention consists of a piece of wire 8 which must be flexible, and is generally made of spring steel. The wire is looped at 9 intermediately of its length to pass around, and rest on, the shank 5 of the door knob 4. The legs 10 of the wire cross one another between the loop 9 and their ends, and one is made longer than the other as shown in the drawings. Longitudinally the legs are generally slightly bowed so that where they cross they will tend to rest against one another.

The wire must be sufficiently resilient to be placed around a shank 5. Its ends, or legs, 10 are then lowered towards the key 6 until one has entered the opening 7; the other leg may then be easily brought into position to enter the said opening. When this has been accomplished the wire is pushed down until its loop 9 rests around the upper side of the shank 5.

By flexing the legs longitudinally, both in the same direction it is found that whichever one is over the other they may be more easily made to rest against one another where they cross. Further when the wire is so placed

that the legs curve towards the door greater force is needed to move the key outwardly against the spring tension of the wire, though in any case the key cannot be dislodged from its lock until it has been turned into a vertical position and to do so is virtually impossible as long as the legs 10 project through the key opening 7.

While in the foregoing the preferred embodiment of the invention has been described and shown, it is understood that the invention is subject to such modifications as fall within the scope of the appended claim.

What I claim as my invention and desire to secure by Letters Patent is:

A key fastener formed of a piece of resilient wire so flexed intermediately of its length as to form two straight leg portions of unequal length, said leg portions being relatively so directed that they cross one another adjacent their extremities, the flexed intermediate portion of the wire being adapted to partly encircle the shank of a door handle, the crossed leg portions being adapted to hold the wire against accidental disengagement from the shank, and the extremities of the legs being laterally inclined from one another and adapted to project through a loop formed in the end of a key.
